(57) **CLAIM**

The ornamental design for adjustable fishing pole support and tip-up, as shown and described.

DESCRIPTION

FIG. 1 is a front elevational view of an adjustable fishing pole support and tip-up embodying a preferred form of the invention, with the tip-up shown in a non-signalling position;

FIG. 2 is an exploded front elevational view of the adjustable fishing pole support and tip-up of FIG. 1;

FIG. 3 is a rear elevational view;

FIG. 4 is a top plan view;

FIG. 5 is a side elevational view as seen from the left of FIG. 1;

FIG. 6 is a side elevational view as seen from the right of FIG. 1; and,

FIG. 7 is a front elevational view similar to FIG. 1, with the tip-up being shown in a signalling position to indicate a fish bite.

The drawing views are shown broken away for convenience of illustration.
